UNITED STATES PATENT OFFICE.

FRIDOLIN POLZER, OF NEW YORK, N. Y.

DESIGN FOR A STAPLING-MACHINE FRAME.

60,105.

Specification for Design.

Patented Dec. 27, 1921.

Application filed September 11, 1920. Serial No. 409,714. Term of patent 14 years.

To all whom it may concern:

Be it known that I, FRIDOLIN POLZER, a citizen of the United States, residing at New York city, in the county of New York and State of New York, have invented a certain new, original, and ornamental Design for a Stapling-Machine Frame, of which the following is a specification, reference being had to the accompanying drawing, forming part thereof.

Figure 1 is a side elevation of a stapling

machine frame made in accordance with my invention, and

Fig. 2 is a view of the opposite side of the same stapling machine frame.

I claim:

The ornamental design for a stapling machine frame as shown.

In testimony that I claim the foregoing, I have hereunto set my hand this 9th day of September, 1920.

FRIDOLIN POLZER.
